US00D728587S

(12) **United States Design Patent**
Leyden

(10) **Patent No.:** **US D728,587 S**
(45) **Date of Patent:** **** May 5, 2015**

(54) **DISPLAY WITH GRAPHICAL USER INTERFACE**

(71) Applicant: **Adobe Systems Incorporated**, San Jose, CA (US)

(72) Inventor: **Mark C. Leyden**, Oxford Mills (CA)

(73) Assignee: **Adobe Systems Incorporated**, San Jose, CA (US)

(**) Term: **14 Years**

(21) Appl. No.: **29/484,064**

(22) Filed: **Mar. 5, 2014**

Related U.S. Application Data

(62) Division of application No. 29/373,205, filed on Mar. 17, 2011, now Pat. No. Des. 715,324.

(51) **LOC (10) Cl.** **14-04**

(52) **U.S. Cl.** **D14/485**
USPC **D14/485**

(58) **Field of Classification Search**

CPC G06F 3/048; G06F 3/0481; G06F 3/04817
USPC D14/485-495

(57) **CLAIM**

The ornamental design for a display with graphical user interface, as shown and described.

DESCRIPTION

The FIGURE is a front elevation view of a display with graphical user interface, showing my new design.

The broken line illustrating the display screen and portions of the graphical user interface illustrate environmental features and form no part of the claimed design.

1 Claim, 1 Drawing Sheet
